UNITED STATES PATENT OFFICE.

CLARENCE NEWTON SCOTT, OF HOUSTON, TEXAS, ASSIGNOR TO THE TEXAS COMPANY,
OF HOUSTON, TEXAS.

DESIGN FOR AN ADVERTISING DEVICE FOR DISPLAYING OIL.

44,692.

Specification for Design.

Patented Sept. 23, 1913.

Application filed February 17, 1913. Serial No. 749,043. Term of patent 14 years.

To all whom it may concern:

Be it known that I, CLARENCE NEWTON SCOTT, residing at 2117 Milam street, city of Houston, county of Harris, State of Texas, have invented a new, original, and ornamental Design for an Advertising Device for Displaying Oil, of which the following is a specification, reference being had to the accompanying drawing, forming part thereof.

The figure is a plan view of an oil container showing my new design.

I claim:

The ornamental design for an advertising device for displaying oil as shown.

CLARENCE NEWTON SCOTT.

In the presence of—

W. E. LOCKHART,
CHAS. H. LANE.
